UNITED STATES PATENT OFFICE.

EDWARD HETT, OF NEW YORK, N. Y.

PRINTING FORM AND PRESS.

SPECIFICATION forming part of Letters Patent No. 662,865, dated November 27, 1900.

Application filed November 20, 1899. Serial No. 737,652. (No model.)

To all whom it may concern:

Be it known that I, EDWARD HETT, a citizen of the United States, and a resident of New York, (New Dorp,) county of Richmond, and 5 State of New York, have invented certain new and useful Improvements in Printing Forms and Presses, of which the following is a specification.

This invention relates to presses, and more 10 particularly to printing-forms and their supports.

The invention seeks to provide printing-forms made of any suitable material and which may be used for relief or intaglio printing, but especially such as are adapted for 15 lithographic printing, the term "lithographic" being employed herein in its generic sense and not limited to the use of stone.

The invention consists in the features of 20 construction and arrangement hereinafter set forth.

In the accompanying drawings, forming 25 part of this specification, I have illustrated some of the different embodiments capable of expressing my invention.

Figure 1 is a longitudinal sectional elevation permanently secured to a shaft and mounted in a press. Figs. 2, 3, and 4 are sectional elevations on the lines 2 2, 3 3, and 30 4 4, respectively, and looking in the direction of the arrows: Fig. 5 is a longitudinal sectional elevation of a printing-form removable from end journals and supported by the press. Fig. 6 is a similar view of a printing-form removable from a supporting-shaft. Fig. 7 is a similar view of a printing-form having permanently-attached end journals. Fig. 8 is a similar view of a printing-form removable from its shaft. Fig. 9 is a side elevation, partially in section, showing a printing-press in diagram.

Referring now particularly to the structural details illustrated in the drawings, and first to the printing-forms shown in Figs. 1, 2, 3, 45 and 4, 1 is a printing-form permanently secured on the shaft 2, so that the printing-form and shaft may be removed from and replaced in a press together. On the shaft near one end is keyed a collar 3, having slots 50 through which set-screws 5 pass into the end of the printing-form. The collar 3 has a tongue 6, against which abut the set-screws

7 and 8, secured on the end of the printing-form. On the opposite end of the printing-form is keyed a collar 9, having slots 10, 55 through which set-screws 11 pass into the end of the printing-form. 12 is a driving-gear abutting the collar 9 and keyed on the shaft 2. 13 and 14 are bushings adjustable in the boxes 15 and 16 and secured in place by the 60 set-screws 17 and 18. When the printing-form is first mounted on its shaft, the set-screws 7 and 8 may be employed to adjust the printing-form circumferentially on this shaft to the proper position, the screws 11 65 being loosened to permit this to be done. The longitudinal adjustment of the printing-form between the boxes 15 and 16 is accomplished by adjusting the bushings 13 and 14. The gear 12 has a marked tooth, by means of which 70 as a guide the precise predetermined circumferential position of the printing-form may be at once attained with respect to the coöperating parts of the press. This marked tooth may always enter a marked recess in a coöperating gear in a printing-press, or it may enter a marked recess on the coöperating part of a transfer-press. The precise predetermined 75 longitudinal position of the printing-form in the press may be at once attained by the bushing 14, against which the hub of the gear 12 is made to accurately fit when the printing-form is removed and then replaced in the press. In removing the printing-form the box 15 is disconnected from the arm 19 and is then 80 removed, together with its bushing 13. The printing-form, with the shaft 2, is then free to be removed from the press and without removing the box 16. The printing-form has a body of such strength as to be capable of 85 itself withstanding the pressure incident to transferring a design upon the printing-form and to printing with such printing-form. If desired, however, I may provide the interior of the printing-form with a brace 20, adapted to 90 bear against the shaft and calculated to give additional strength to the form. The form 1 is preferably hollow, as shown, and is made of any suitable material and has on its exterior an electrolytically-deposited coating of copper 21, upon which is another electrolytically-deposited coating of zinc 22. These coatings are integral with each other and with the underlying surface of metal and may be re-

moved by dissolving them in acid, so as not to change the size and form or their support, which may be predetermined. I may, if desired, use only one coating.

5 In Fig. 5 the printing-form 23 is hollow and has a body of such strength as to be capable of itself withstanding the pressure incident to transferring and printing. It consists of a base 24, having an external printing-surface 10 25 of a different material, which is removable from and renewable on the base. This base may be made of aluminium, and the exterior coating 25 may be zinc electrolytically deposited upon another coating 26 of a suitable 15 metal, such as copper, electrolytically deposited upon the base. The form is supported in and removable from the boxes 27 and 28 of the press by means of the end journals 29 and 30, from which the form is removable. Tapped 20 in the heads of the form are the bushings 31 and 32, into which enter the journals 29 and 30. These journals are threaded for a short distance at their outer ends, so as to screw 25 into the boxes. The journals are held from turning when in place by the locks 33 and 34 bearing against the octagonal heads formed on the journals. 35 is a gear secured on the end of the form and having a marked tooth for the same purpose as the marked tooth referred 30 to in connection with Fig. 1. In removing the form from the boxes the journals are unlocked and removed from engagement with the form, which may then be removed from the press. Bushings 31 and 32 after being 35 primarily adjusted and fixed in the ends of the form by their set-screws form guides with reference to which the form is mounted in the press in accurate predetermined longitudinal position, the bushings fitting snugly 40 against the boxes.

In Fig. 6 the printing-form 36 is of metal and preferably aluminium and is hollow, and its body is of suitable strength, such as described. It is supported on the shaft 37, on 45 which are permanently keyed the heads 38 and 39, fitting the interior of the form. 40 is a gear having a marked tooth for the purpose already described in connection with the gear in Fig. 1. Projecting from the outer 50 sides of the heads 38 and 39 are collars having threaded recesses 41 and 42, in which screw the collars 43 and 44, the collars being held in adjusted position by set-screws. These 55 collars hold the shaft 37 accurately in place in its boxes 45 and 46. In removing the form the clamps 47 are loosened and the form slipped lengthwise from the heads 38 and 39. The longitudinal position of the form on the shaft is determined by the offset 48 coming 60 flush against the head 38, and the circumferential position of the form on the shaft is determined by the ribs on the inner side of the form fitting accurately in corresponding 65 grooves formed in the peripheries and the heads 38 and 39. 50 is an interior support keyed on the shaft 36 and serving to additionally strengthen the printing-form.

In Fig. 7 is shown a solid aluminium printing-form 51. It is provided at its ends with journals 52 and 53, permanently secured in 70 place. On the journal 52 is secured a gear 54, having a marked tooth for the same purpose as that referred to in connection with the marked tooth of the gear in Fig. 1. 55 and 56 are threaded collars adapted to be adjusted on the threaded portions of the journals 52 and 53 and then permanently locked in place by their set-screws. The collars 55 and 56 are adjusted so as to fit accurately between the boxes 57 and 58, these collars determining the longitudinal position of the printing-form in the press. When the form is to be removed from the press, either the box 57 or 58 is first removed and the form, together with its journals, gear-wheel, and 80 collars 55 and 56, may be taken from the press.

In Fig. 8 is shown a hollow metallic removable form of suitable strength, such as has been described and preferably made of aluminium. It is removable from and replaceable 90 on its shaft 60. The heads of the form are provided with ribs 61 and 62, which slide in a corresponding groove 63 in the shaft 60 and determine a circumferential position of the form on its shaft. Screwed on the shaft are 95 the adjustable collars 64 and 65, adapted to be locked in place by set-screws. 66 is a gear having a marked tooth for the same purpose as the marked tooth of the gear already referred to in connection with Fig. 1. The shaft 100 60 is supported in boxes 67 and 68. In removing the printing-form from the press the box 68 and the collar 65 are detached from the shaft, when the form may be slipped lengthwise from the shaft. The collar 64, 105 which remains on the shaft, determines the longitudinal position of the form on its shaft when the form is replaced.

If desired, the printing-forms may be solid all the way through and removable from their 110 shafts or permanently connected therewith by being keyed or cast thereon or otherwise connected therewith, or I may make a printing-form hollow or solid, any of these various kinds of forms having end journals permanently attached thereto. Printing-forms 115 may be developed so as to be capable of relief or intaglio printing; but they are preferably developed so as to be lithographic printing-surfaces. They are preferably cylindrical, with continuous unbroken surfaces for 120 printing.

In Fig. 10 is shown a series of my printing-forms supported in position around an impression-surface 69, the marked tooth on the 125 gear of each form entering a marked recess of the gear 70 of the impression-surface 69.

The printing-forms are preferably made by painstakingly shaping and forming and sizing and proportioning the body of the form 130 and finishing and leveling its surface in every minute portion to the exact shape and form and size and printing height and plane required in the press, and where a coating is

applied to the body the characteristics of the complete composite form as to size, shape, and uniform height and plane are determined by these features of the body. This feature of 5 the invention is not restricted to a curve or rotating printing-form.

What I claim, and desire to secure by Letters Patent, is—

1. In a press the combination of a rotating 10 lithographic printing-form having a body of such strength as to be capable of itself withstanding the pressure incident to transferring and printing, with preëstablished guides with reference to which the printing-form may be arranged in accurate predetermined relation with the coöperating parts of the press and 15 without the usual empiric adjustment.

2. In a press a combination of a hollow rotating lithographic printing-form having a 20 body of such strength as to be capable of itself withstanding the pressure incident to transferring and printing, with preëstablished guides with reference to which the printing-form may be arranged in accurate predetermined relation with the coöperating parts of 25 the press and without the usual empiric adjustment.

3. In a press a combination of a rotating lithographic metallic printing-form having a 30 body of such strength as to be capable of itself withstanding the pressure incident to transferring and printing, with preëstablished guides with reference to which the printing-form may be arranged in accurate predetermined relation with the coöperating parts of 35 the press and without the usual empiric adjustment.

4. In a press the combination of a rotating lithographic aluminium printing-form having a 40 body of such strength as to be capable of itself withstanding the pressure incident to transferring and printing, with preëstablished guides with reference to which the printing-form may be arranged in accurate predetermined relation with the coöperating parts of the press and without the usual empiric 45 adjustment.

5. In a press the combination of a hollow rotating lithographic metallic printing-form 50 having a body of such strength as to be capable of itself withstanding the pressure incident to transferring and printing, with preëstablished guides with reference to which the printing-form may be arranged in accurate predetermined relation with the coöperating parts of the press and without the usual empiric 55 adjustment.

6. In a press the combination of a hollow rotating lithographic aluminium printing-form 60 having a body of such strength as to be capable of itself withstanding the pressure incident to transferring and printing, with preëstablished guides with reference to which the printing-form may be arranged in accurate predetermined relation with the coöperating parts of the press and without the usual empiric 65 adjustment.

7. In a press the combination of a rotating lithographic printing-form having a body of such strength as to be capable of itself withstanding the pressure incident to transferring and printing, with preëstablished guides with reference to which the printing-form may be arranged in accurate predetermined relation with the coöperating parts of the press and 70 without the usual empiric adjustment, said printing-form having a continuous unbroken exterior surface for printing.

8. In a press a combination of a hollow rotating lithographic printing-form having a 80 body of such strength as to be capable of itself withstanding the pressure incident to transferring and printing, with preëstablished guides with reference to which the printing-form may be arranged in accurate predetermined relation with the coöperating parts of the press and without the usual empiric adjustment, said printing-form having a continuous unbroken exterior surface for printing.

9. In a press the combination of a rotating lithographic printing-form having a body of such strength as to be capable of itself withstanding the pressure incident to transferring and printing, with preëstablished guides with reference to which the printing-form may be 90 arranged in accurate predetermined relation with the coöperating parts of the press and without the usual empiric adjustment, said printing-form having an exterior removable and renewable coating to provide the surface 95 for printing.

10. In a press the combination of a rotating lithographic metallic printing-form having a body of such strength as to be capable of itself withstanding the pressure incident to transferring and printing, with preëstablished guides with reference to which the printing-form may be arranged in accurate predetermined relation with the coöperating parts of the press and without the usual empiric adjustment, said printing-form having an exterior removable and renewable coating to provide the surface 100 for printing.

11. In a press the combination of a rotating lithographic printing-form having a body of such strength as to be capable of itself withstanding the pressure incident to transferring and printing, with preëstablished guides with reference to which the printing-form may be arranged in accurate predetermined relation with the coöperating parts of the press and without the usual empiric adjustment, said printing-form having an electrolytically-deposited coating to provide the surface for 115 printing.

12. In a press a combination of a rotating lithographic metallic printing-form having a body of such strength as to be capable of itself withstanding the pressure incident to transferring and printing, with preëstablished 120 guides with reference to which the printing-form may be arranged in accurate predetermined relation with the coöperating parts of the press and without the usual empiric adjustment, said printing-form having an electrolytically-deposited coating to provide the surface for 125 printing.

justment, said printing-form having an electrolytically-deposited coating to provide the surface for printing.

13. In a press the combination of a rotating lithographic printing-form having a body of such strength as to be capable of itself withstanding the pressure incident to transferring and printing, with preëstablished guides with reference to which the printing-form may be 10 arranged in accurate predetermined relation with the coöperating parts of the press and without the usual empiric adjustment, said printing-form being accurately sized and shaped and finished to adapt it to the coöperating parts of the press.

14. In a press a combination of a rotating lithographic metallic printing-form having a body of such strength as to be capable of itself withstanding the pressure incident to 20 transferring and printing, with preëstablished guides with reference to which the printing-form may be arranged in accurate predetermined relation with the coöperating parts of the press and without the usual empiric adjustment, said printing-form being accurately sized and shaped and finished to adapt it to the coöperating parts of the press.

15. In a press the combination of a rotating printing-form having a body of such strength 30 as to be capable of itself withstanding the pressure incident to transferring and printing, with preëstablished guides with reference to which the printing-form may be arranged in accurate predetermined relation with the coöperating parts of the press and without the usual empiric adjustment.

16. In a press the combination of a rotating printing-form having a body of such strength as to be capable of itself withstanding the 40 pressure incident to transferring and printing, with preëstablished guides with reference to which the printing-form may be arranged in accurate predetermined relation with the coöperating parts of the press and without the usual empiric adjustment, said printing-form having a continuous unbroken exterior surface for printing.

17. In a press the combination of a rotating printing-form having a body of such strength 50 as to be capable of itself withstanding the pressure incident to transferring and printing, with preëstablished guides with reference to which the printing-form may be arranged in accurate predetermined relation with the coöperating parts of the press and without the usual empiric adjustment, said printing-form having an exterior removable and renewable coating to provide the surface for printing.

18. In a press the combination of a rotating printing-form having a body of such strength as to be capable of itself withstanding the 60 pressure incident to transferring and printing, with preëstablished guides with reference to which the printing-form may be arranged in accurate predetermined relation with the coöperating parts of the press and without

the usual empiric adjustment, said printing-form having an electrolytically-deposited coating to provide the surface for printing.

19. In a press the combination of a rotating printing-form having a body of such strength as to be capable of itself withstanding the pressure incident to transferring and printing, with preëstablished guides with reference 70 to which the printing-form may be arranged in accurate predetermined relation with the coöperating parts of the press and without the usual empiric adjustment, said printing-form being accurately sized and shaped and finished to adapt it to the coöperating parts of the press.

20. In a printing-press the combination of a series of rotating printing-forms each having a body of such strength as to be capable of itself withstanding the pressure incident to printing, with devices for inking the forms, and guides with reference to which said forms may be arranged in accurate predetermined relation with the coöperating parts of this 80 press and without the usual empiric adjustment.

21. In a printing-press the combination of a series of rotating printing-forms each having a body of such strength as to be capable of itself withstanding the pressure incident to printing, with devices for inking the forms and guides with reference to which said forms may be arranged in accurate predetermined relation with the coöperating parts of the 90 press and without the usual empiric adjustment, each of said forms having a continuous unbroken exterior surface for printing.

22. In a printing-press the combination of a lithographic printing-form having a body of such strength as to be capable of itself withstanding the pressure incident to transferring and printing, said body having the exact size and shape and being of uniform height and plane such as will adapt it when 100 provided with a suitable coating to coöperate subsequently as a printing-surface with the other parts of a press in printing, said body being provided with a uniformly thick even layer or coating of material adapted to provide a surface for printing, the characteristics of the surface of the printing-form as to size and shape and height and level being determined by those of the base and preëstablished guides with reference to which said 110 form may be arranged in accurate predetermined relation with the coöperating parts of the press and without the usual empiric adjustment.

23. In a printing-press the combination of a rotating lithographic printing-form having a body of such strength as to be capable of itself withstanding the pressure incident to transferring and printing, said body having the exact size and shape and being of uniform 120 height and plane such as will adapt it when provided with a suitable coating to coöperate subsequently as a printing-surface with the other parts of a press in printing, said body 130

being provided with a uniformly thick even layer or coating of material adapted to provide a surface for printing, the characteristics of the surface of the printing-form as to size and shape and height and level, being determined by those of the base and preëstablished guides with reference to which said form may be arranged in accurate predetermined relation with the coöperating parts of

the press and without the usual empiric adjustment.

In testimony whereof I have signed my name to this specification in the presence of two subscribing witnesses.

EDWARD HETT.
